(57) **CLAIM**

The ornamental design for a chock as shown and described.

DESCRIPTION

FIG. 1 is a top, front, right perspective view of the claimed design for a chock;

FIG. 2 is a front view of the claimed design of FIG. 1;

FIG. 3 is rear view of the claimed design of FIG. 1;

FIG. 4 is a right side view of the claimed design of FIG. 1;

FIG. 5 is a left side view of the claimed design of FIG. 1;

FIG. 6 is a top view of the claimed design of FIG. 1; and,

FIG. 7 is a bottom view of the claimed design of FIG. 1.

The ornamental design that is claimed is shown in solid lines in the figures. The broken lines in the drawings are for illustrative purposes only and form no part of the claimed design. Broken lines formed by equal or substantially equal length dashes show unclaimed portions of the design and form no part of the claimed design. Broken lines formed of unequal length dashes (i.e., dash-dot-dash) show boundaries between claimed and unclaimed portions of the design. Any shading lines in the drawings show contour and not surface ornamentation.
